[57] CLAIM

The ornamental design for a wax applicator housing, as shown and described.

DESCRIPTION

FIG. 1 is a perspective view of a wax applicator housing showing our new design.

FIG. 2 is a side elevational view thereof, the opposite side being substantially a mirror image thereof,

FIG. 3 is a plan view thereof,

FIG. 4 is a rear end elevational view thereof, and

FIG. 5 is a front end elevational view thereof.
The broken line disclosure in FIG. 1 is for illustrative purposes only and forms no part of the claimed design.
